PROCESS OF MAKING METALLIC BARRELS.

1,054,105.

Specification of Letters Patent.

Patented Feb. 25, 1913.

Application filed June 24, 1912. Serial No. 705,631.

To all whom it may concern:

Be it known that I, DAVID B. GALBALLY, a citizen of the United States, residing at New York, in the county of New York and State 5 of New York, have invented certain new and useful Improvements in Processes of Making Metallic Barrels; and I do hereby declare the following to be a full, clear, and exact description of the invention, such as 10 will enable others skilled in the art to which it appertains to make and use the same.

This invention relates to a method of making metallic barrels from individual flat stave pieces, and has for its object to provide 15 a series of steps by which a strong liquid-tight bilge barrel can be made without rendering it necessary to employ expensive presses or other heavy machinery for dishing or curving the staves.

20 To these ends the invention consists in the novel steps and combinations of steps more fully hereinafter disclosed and particularly pointed out in the claims.

Referring to the accompanying drawings 25 forming a part of this specification in which like numerals designate like parts in all the views: Figure 1 is a diagrammatic view, illustrating a pair of flat staves placed edge to edge preparatory to being curved to 30 shape. Fig. 2 is a view similar to Fig. 1, illustrating the operation of forcing the locking strip over the meeting edges of the staves in order to bind them together and simultaneously curve them to shape. Fig. 3 35 is an enlarged sectional view, in perspective, of the joint formed between the staves. Fig. 4 is a view similar to Fig. 3, but illustrating the flanged head portion of the barrel. Fig. 5 is a top plan view of the barrel with the 40 head removed, and Fig. 6 is a longitudinal 45 sectional view of a completed barrel employing my joint.

In order that my method of making a strong and tight joint while at the same time curving the staves, may be clearly understood, it is said:—1 indicates flat staves cut from flat metal sheets by any suitable means. These staves are provided along their ends with the offset flanges 2, providing the seats 50 3 for the head 4, and have along their longitudinal edges the locking flanges formed by turning up said edges, by any suitable means, so that each, when in the position shown in Fig. 3 will be composed of a vertical member

5, a horizontal member 6, a second vertical 55 member 7 and a second horizontal member 8.

In order to firmly lock the flanges of two adjacent staves together, I provide the locking strip 22, formed from a single flat piece of metal so bent upon itself that one edge, 60 when in the position illustrated in Fig. 3, forms the horizontal member 9, fitting between the body of the staves and the first horizontal member 6 of its locking flange. Said locking strip 22 is further so bent as to 65 provide the vertical member 10 extending at right angles to the member 9, and extending parallel to the member 7 of the locking flange when in contact therewith. The said locking strip is further bent so as to provide 70 the second horizontal member 11, extending at right angles to the member 10, and bent again at right angles to the said second horizontal member 11 to form the second vertical member 12, and then bent at right angles to 75 the said second vertical member 12 to form the third horizontal member 13. After being bent at right angles to form the third horizontal member 13, as above described, the material of the said locking strip 22 is 80 next bent flat back upon itself to form the fourth horizontal member 14, which extends twice the length of the said third member 13, wheretupon it is again bent flat upon itself 85 to form a fifth horizontal member 15, and then at right angles to the member 15 to form a third vertical member 16. From the member 16 the material of the locking strip 22 extends at right angles to form the sixth horizontal member 17, and then at right angles to the member 17 to form the fourth vertical member 18, and finally at right angles to the member 18 to form the seventh horizontal member 19, which constitutes the 90 other edge of the said locking strip 22. 95

In forming the locking flanges on the staves 1, the first vertical members 5 are made of a length just sufficient to cause the first horizontal members 6 to be located a distance away from the body of the stave 1 100 to form recesses for the snug accommodation of the horizontal members 9 and 19 of the locking strip 22, while the spaces left on said locking flanges between the horizontal members 6 and 8 are just sufficient to snugly 105 accommodate the parallel bent members 13 and 14, and 14 and 15, respectively, of the locking strip. Further, the vertical mem-

bers 12 and 16 of the locking strip are chosen of proper dimensions to afford recesses adapted to snugly accommodate the horizontal members 8 of the locking flanges. It 5 results from the structure just disclosed that when the parts are in the positions indicated in Fig. 3, each member of the locking flanges is inclosed by one or more members of the locking strip 22, and that while the vertical 10 members 5 of two adjacent flanges are brought into contact to form a tight joint at 20, the members 13, 14 and 15 constitute a firm brace or stiffening rib which causes said joint to effectually resist strains of all kinds 15 that may be brought upon the finished barrel.

Further it will be observed that the staves 1 are cut out of flat material with curved edges, as shown. It therefore follows that if their curved edges are brought together 20 as illustrated in Fig. 1, the said edges cannot meet in the plane indicated by the dotted line 21, unless the bodies of said staves are curved into a concavo-convex shape. But it is further evident, on the other hand, that 25 if the said edges are brought together, as illustrated in Fig. 2, and the locking strip 22 driven or otherwise forced into the position as shown in Figs. 3 to 6, then the curved edges of said flat staves 1 will be forced to 30 meet in a plane such as 21, and the body portions of said staves will thereupon be forced to assume a concavo-convex shape as a result of said driving action. Further, the 35 flexing of the stave bodies, in the manner indicated, results in a wedging action between the parts, as well as in a setting up of stresses in the metal, causing the interlocking members of the stave flanges and locking strip to be put under a tension. It follows, 40 as a result of the complex tensioning strains thus set up, that a joint 20 of extraordinary tightness and stability is produced. In addition to the above, this joint or seam 20, is bridged by the tightly fitting, longitudinally 45 curved, bracing member 14, which further insures against leakage.

The entire construction offers no edges which can be broken by bending or twisting while rolling the barrel, and it is found in 50 practice to be the strongest part of the barrel. The locking pieces 22, after being driven home, are cut off even with the seats 3, at each end of the barrel, and their ends form additional supports for the heads 4.

It will also be observed that the longitudinally curved members 14 of the locking pieces 22, which bridge the seam 20, being 55 located on the inside of the transversely and longitudinally curved staves, acts somewhat like the keystone of an arch, and prevents the staves from shifting after the hoops 24 are put on.

It will be seen that by first cutting the staves out of flat material with properly 60 curved longitudinal edges, I do away with

the necessity of employing expensive machinery to curve the staves, for my whole process can either be carried out by hand or with the aid of light, and comparatively inexpensive machinery. The necessary curve 70 on the edges of the staves to form the desired bilge barrel may be obtained in a variety of ways, but I prefer to simply take a stave from a barrel having the desired shape, flatten out said stave, work out its 75 contour in a flat state, and then add sufficient material to form the locking flanges.

It is obvious that those skilled in the art may vary the details of my process without departing from the spirit thereof, and therefore I do not wish to be limited to the above disclosure except as may be required by the 80 claims.

What I claim is:—

1. The process of making metallic bilge 85 barrels from individual staves and sealing the seams between said staves which consists in providing flat staves with curved longitudinal edges; forming on said edges curved locking flanges each having an outer and an inner recess opening in opposite directions; abutting together the ends of two opposing flanges with their inner recesses in register; providing a locking strip having opposing edges adapted to enter the said outer recesses 90 of said opposing flanges, and having an intermediate stiffening rib adapted to enter the said registering inner recesses and to seal the seam between said flanges; and forcing the said locking strip over and between said 100 flanges thereby causing said curved flanges to meet in a single sealed seam throughout their length and said staves to be curved longitudinally and transversely into the contour of said barrel, substantially as described. 105

2. The process of curving transversely and longitudinally flat metallic staves having curved edges which consists in providing said edges with locking flanges, and then longitudinally forcing a locking strip over 110 said flanges to cause said flanges to meet throughout their length in a single seam, substantially as described.

3. The process of making a bilge barrel from individual flat metallic staves having 115 curved edges which consists in providing said edges with locking flanges; causing the ends of opposing flanges to meet; and longitudinally driving locking strips over and between said opposing flanges until they 120 have met in continuous seams, thereby causing said staves to curve into the contour of said barrel, substantially as described.

4. The process of making a bilge barrel from individual flat metallic staves having 125 curved edges and simultaneously sealing the seams between opposing edges which consists in providing said edges with locking flanges; having inner and outer locking recesses; causing the ends of opposing flanges to con- 130

tact; and longitudinally forcing locking strips over said flanges and in said recesses until said flanges have met in single sealed seams, substantially as described.

- 5 5. The method of forming a liquid tight seam between two metallic staves and simultaneously shaping said staves to the contour of a bilge barrel which consists in suitably forming flat individual staves each 10 having convex edges; forming locking flanges on said staves having convex outer vertical walls and concave inner vertical walls; abutting a pair of opposite convex

walls on said flat staves; and forcing a locking member over said convex inner walls 15 thereby drawing said convex outer walls together from end to end, and simultaneously forcing said staves to assume the contour of a finished bilge barrel, substantially as described. 20

In testimony whereof I affix my signature, in presence of two witnesses.

DAVID B. GALBALLY.
